UNITED STATES PATENT OFFICE.

CHARLES SEYBOLD, OF CINCINNATI, OHIO, ASSIGNOR TO SEYBOLD & SCHLUETER, OF SAME PLACE.

PALLET.

SPECIFICATION forming part of Letters Patent No. 358,791, dated March 1, 1887.

Application filed August 13, 1885. Serial No. 174,255. (No model.)

To all whom it may concern:

Be it known that I, CHARLES SEYBOLD, a resident of Cincinnati, Hamilton county, Ohio, have invented certain new and useful Improvements in Pallets, of which the following is a specification.

My device is intended for holding type and securing them in a position to be used. In lettering the covers of books and the like, and in lettering stamps, it is desirable to have a holder in which the length of line or distance between the jaws can be quickly and easily changed. My device provides for this ready change.

15 In the accompanying drawings, Figure 1 is a front elevation of my device. Fig. 2 is a view of the same with the front (side) plate of the box removed. Fig. 3 is a central cross-section taken through the axis of the handle. 20 Fig. 4 shows the attachment of the changing-screw to its adjacent rack-plate. Fig. 5 shows one rack in perspective. Fig. 6 shows the other rack in perspective.

The box B is supported on any appropriate handle, A. The box consists of an anterior face, B', and a posterior face, B'', and a bottom, B''. These are preferably cast in one piece. The ends are closed, preferably, by caps B'. Lips b b extend over the top of the 25 box from the sides B', B'', and leave a slot between them, which extends the whole length of the box. The jaws D rest on the top of the box formed by the lips b b, and slide back and forth thereon.

30 Each jaw D has a web or connecting-shank, d, which projects downwardly and unites the body of the jaw to a flange, d', beneath. When in position, the web d fits in the slot, and the flange d', catching under the lips b b, prevents the jaw D from slipping out. A tooth, d'', projects downward from each flange d'. The lip B'' is a continuation of the side B''. It extends nearly the length of the box B. In the box are two racks, E and F. (Shown in perspective in Figs. 5 and 6.) The rack E has a series of teeth, e, extending across it. The flat tongue e' is considerably lower than the teeth and beveled beneath its free end, as shown at e''. The groove e'' extends entirely across the 35 bottom of the rack. The screw S is secured

to rack E, and so connected thereto as to be capable of rotation, while the rack E does not turn. The preferred mode of making such connection is as follows: In the thick end of the rack E a recess, e⁴, is cut. This recess is preferably cut through the entire thickness of the rack, and at its opening on the end of the rack the recess is contracted to form the slot e⁵. The rack F is of such thickness that when it rests on the tongue e' the top of its teeth will be on 55 a level with the top of the teeth of rack E. The thumb-screw S screws into the projection b. The end of this screw is provided with head s, connected to the shank of the screw by a neck, s'. This head s is swiveled in the 60 recess e⁴, as shown in Fig. 4. The rack E is put on the floor of the box, as shown in Fig. 2. The pin P extends from side to side of the box, just in front of the beveled end of the rack E. The pin P' extends from side to side 65 of the box B, through the groove e². The rack F rests on the tongue e' and abuts against the pin P⁴. The pin P³ is so placed as to prevent the jaws D from respectively passing the middle line. Instead of pins, other mechanical 70 equivalents may be used; but pins are convenient, because they are readily inserted and perform the desired function. When the two racks are in position, as shown in Fig. 2, it 75 will be noticed that a space, G, exists between the inner end of rack F and the series of teeth e of rack E.

The mode of operation is as follows: The jaws D are set at any required distance apart. Then a turn or two is given to the screw S. 85 This movement forces the rack E to the left. As it moves to the left the rack E mounts onto the pins P and P', carrying the rack F up with it. This elevation is sufficient to cause the teeth of the racks to engage with the teeth d'' 90 of the jaws, and this engagement locks the jaws in the desired position. A turn or two of the screw S in the opposite direction lowers the racks and releases the jaws. It only requires a turn or two of the screw S to raise 95 the racks so that they fix the jaws D. A continued turning of the screw S, after the racks have engaged with the teeth of the jaws, forces the rack E bodily to the left, and with it the corresponding jaw D. This movement can 100

be carried to the extent of the space G. This movement is very useful. The jaws D are set by hand at the approximate distance apart. They are then clamped by a turn of the screw 5 S. The type, if not previously set between the jaws, are now set there, and a slight space remains, which is ordinarily filled by quadrats; but with my device the quadrats are dispensed with, and the jaw D is moved to the left by 10 the screw S, as already described, and the type clamped in position.

My device is adapted for other uses than that of a pallet. Notably, it may be used for a vise.

15 The device is simple in structure, not liable to derangement, and cheap in manufacture.

While the various features of my invention are preferably employed together, one or more of said features may be employed without the 20 remainder. One or more of said features may, so far as applicable, be employed in devices for holding or grasping other than the device particularly herein set forth.

What I claim as new and of my invention, 25 and desire to secure by Letters Patent, is—

1. The jaws D, in combination with racks E and F, the jaws being provided with teeth d^2 , which are arranged to engage with teeth of the racks, and mechanism, substantially as described, for advancing rack E and raising the 30 racks, respectively, into engagement with the adjacent tooth d^2 , as for the purpose set forth.

2. The jaws D, sliding on lips b b' , each jaw being provided with web d , flange d' , and tooth

d^2 , in combination with the racks E and F, and mechanism, substantially as described, for raising the latter, substantially as and for the purposes specified.

3. The jaws D, in combination with racks E and F, the jaws being provided with the teeth d^2 , which are arranged to engage with the teeth of said racks when the latter are raised, the said racks being so set as to provide a space, G, between them, as and for the purposes specified.

4. The jaws D, suitably supported, the teeth d^2 , racks E and F, the rack E having tongue e sliding beneath the rack F, and mechanism, substantially as described, for elevating said racks and longitudinally moving rack E, substantially as and for the purposes specified.

5. The combination of a jaw, D, and mechanism, substantially as described, for holding said jaw stationary, and an opposing jaw, D, having a tooth, d^2 , and sliding rack E, and mechanism, substantially as described, for causing this rack to engage said tooth d^2 and for moving said rack longitudinally, substantially as and for the purposes specified.

6. The combination of box B, racks E and F, screw S, pins P, P', and P'', and jaws D, provided with teeth d^2 , as and for the purposes specified.

CHAS. SEYBOLD.
